DAVID BENSON, OF NANUET, NEW YORK.

Design No. 3,230, dated November 10, 1868.

DESIGN FOR A WELL-CURB.

The Schedule referred to in these Letters Patent and making part of the same.

To all whom it may concern:

Be it known that I, DAVID BENSON, of Nanuet, in the county of Rockland, and State of New York, have invented a new and original Design for Well-Curb; and I do hereby declare that the following is a full, clear, and exact description thereof, which will enable others skilled in the art to make and use the same, reference being had to the accompanying photograph, forming part of this specification.

This invention relates to a new and original design for a well-curb, and which is shown in the accompanying photograph.

A is the base, of rectangular or square form, on which the curb rests.

B is the lower part of the curb, which is of quadrilateral square form, having a bead, *a*, at its top, extending around each side, and a recess, *b*, at one side, through which the water is discharged.

On the top of the lower part B, of the curb, at three sides, there are open wire-work panels, C, and above these there is a double-pitch roof, D, having an ornament, *c*, on the peak.

The front panel of the curb is open, with the exception of a bracket, *d*, at each side; and at each angle of the part B of the curb there is a bead, *e*.

Having thus described my invention,
I claim as new, and desire to secure by Letters Patent—

The within-described design for a well-curb, substantially as set forth and shown.

DAVID BENSON.
